[57] CLAIM

The ornamental design for a handle for a fixed blade knife, as shown.

DESCRIPTION

FIG. 1 is a left side elevational view of a handle for a fixed blade knife showing my new design, the right side elevational view being a mirror image thereof;

FIG. 2 is a top plan view thereof;

FIG. 3 is a bottom plan view thereof;

FIG. 4 is a front elevational view thereof; and,

FIG. 5 is a rear elevational view thereof.

The broken line showing of a blade in FIGS. 1-4 is environmental only and forms no part of the claimed design.

FIG. 4.

FIG. 5.

FIG. 1.

FIG. 2.

FIG. 3.
